UNITED STATES PATENT OFFICE.

JAMES M. LEAVER, OF LONGBEACH, CALIFORNIA.

DRY-KILN FOR LUMBER.

1,039,302.

Specification of Letters Patent. Patented Sept. 24, 1912.

Application filed November 29, 1911. Serial No. 663,102.

To all whom it may concern:

Be it known that I, JAMES M. LEAVER, a citizen of the United States, residing at Longbeach, in the county of Los Angeles and State of California, have invented a new and useful Dry-Kiln for Lumber, of which the following is a specification:

The invention relates to improvements in dry kilns for lumber.

10 The object of the present invention is to improve the construction of dry kilns, more especially that shown and described in an application filed by me on or about July 10, 1911, Serial No. 637,805, and to provide a 15 simple, efficient and comparatively inexpensive dry kiln, equipped above its drying chamber with an intervening space between the same and the roof of the kiln and adapted to mix heated moist air from the 20 kiln with the cold air, and divided into a plurality of separate mixing ducts or chambers, extending across the top of the drying chamber and connected by side ducts or 25 passages with the bottom of the kiln and permitting mixed cold air and the heated moist air to traverse the kiln in opposite 30 directions and producing alternately reverse rotary circulation around the drying chamber, whereby thorough diffusion of heat, moisture and air is secured and the best results obtained for drying lumber.

With these and other objects in view, the invention consists in the construction and novel combination of parts hereinafter fully 35 described, illustrated in the accompanying drawings, and pointed out in the claims hereto appended; it being understood that various changes in the form, proportion, size and minor details of construction, within the 40 scope of the claims, may be resorted to without departing from the spirit or sacrificing any of the advantages of the invention.

In the drawings—Figure 1 is a vertical central longitudinal sectional view of a dry 45 kiln, constructed in accordance with this invention, the section being taken on the line 1—1 of Fig. 6. Fig. 2 is a longitudinal sectional view on the line 2—2 of Fig. 6. Fig. 3 is a horizontal sectional view on the line 3—3 of Fig. 1. Fig. 4 is a similar view on the line 4—4 of Fig. 1. Fig. 5 is a horizontal sectional view on the line 5—5 of Fig. 1. Fig. 6 is a transverse sectional view on the line 6—6 of Fig. 1. Fig. 7 is a 50 similar view on the line 7—7 of Fig. 1. Fig. 8 is a transverse sectional view on the line 8—8 of Fig. 1. Fig. 9 is a transverse sectional view on the line 9—9 of Fig. 1. Fig. 10 is a detail longitudinal sectional view of one of the units or sections of a kiln, illustrating another embodiment of the invention. Fig. 11 is a similar view, illustrating another form of invention. Fig. 12 is a similar view of the opposite side of the section or unit illustrated in Fig. 11.

Like numerals of reference designate corresponding parts in all the figures of the drawings.

The dry kiln illustrated in Figs. 1 to 9 inclusive of the accompanying drawings 70 comprises in its construction, side walls 1 and 2 and a roof 3, designed to be constructed of any suitable material. The dry kiln is provided at the top of its drying chamber 4 with a ceiling or top wall 5, 75 spaced from the roof 3 to form an intervening space for the mixing of cold air with heated moist air from the drying chamber. Instead of equipping the dry kiln with a single continuous mixing chamber, extending 80 from one end of the kiln to the other in the manner illustrated in the aforesaid application, the intervening space between the top wall or ceiling 5 and the roof 3 of the kiln is divided by a plurality of transverse 85 partitions 6 into separate transverse ducts or chambers 7, extending across the top of the drying chamber from one side of the dry kiln to the other and connected with the bottom thereof by ducts or passages, and adapted 90 to permit a circulation of heat, air and moisture around the kiln, the circulation through one mixing duct or chamber 7 being in one direction while the circulation through the next adjacent mixing duct or 95 chamber 7 is in the opposite direction, the sections or units of the kiln being alternately 100 reversely arranged to produce this result and thereby secure a thorough diffusion of heat, air and moisture within the drying chamber. The kiln may consist of any number 105 of these sections or units, and each section or unit is provided at opposite sides of the drying chamber with a series of vertical ducts or passages. At one side of the drying chamber the series of the vertical passages or ducts consists of a suction duct 8, a cold air duct 9 and hot air ducts 10 and 11, located at opposite sides of the cold air duct, the hot air duct 10 being arranged between 110 the suction duct 8 and the cold air duct 9. At the opposite side of the drying chamber,

the section or unit is provided with four vertical return ducts 12 for conducting air from the mixing chamber or duct to the bottom of the drying chamber to points below the plane of the heating pipes 13. The lower portions of the vertical ducts or passages are enlarged and extend inwardly, and the lower portion of the drying chamber is slightly contracted, as clearly shown in Figs. 6 to 9 inclusive. The kiln is provided with a bottom 14, and it has a horizontal partition 15 spaced from the bottom 14 and also from the floor 16 of the drying chamber to form a lower cold air space 17 and an upper space, which is divided by partitions 18 into transverse bottom passages 19, communicating with the lower enlarged portions 20 of the return ducts or passages, and extending across the kiln below the floor 16 and communicating with the interior of the drying chamber by intermediate and side openings 21 and 22, the side openings 22 being of a smaller area than the intermediate openings 21 to cause the greater portion of mixed air to enter the lower portion of the drying chamber at points between the sides of the same. The horizontal bottom ducts 19 are closed at the side of the kiln opposite that at which the return ducts or passages are located. The lower enlarged end 23 of the cold air duct 9 is provided with an opening 24, communicating with the bottom cold air space 17, which has inlet openings 25, located at the ends of the kiln. The ends of the kiln are equipped at the main air inlet openings 25 with slidable doors or closures 26, mounted in suitable guides 27 and adapted to be adjusted to control the volume of cold air admitted to the kiln. The cold air ducts or passages of the various units or sections of the kiln are all connected with the bottom cold air space and receive their supply of cold air from the same. Instead, however, of equipping the dry kiln with the bottom cold air space or conduit 17, cold air may be supplied to the cold air ducts of the various sections or units of the dry kiln in any other preferred manner.

The hot air ducts or passages 10 and 11 are provided with horizontal partitions 28, located at an intermediate point between the top and bottom of the drying chamber and form a wall, which closes the lower portions of the hot air ducts or passages. The said hot air ducts or passages are provided adjacent to and immediately above the horizontal partitions 28 with openings 29, communicating with the interior of the drying chamber, and adapted to permit heated moist air from the same to pass upward through the hot air ducts or passages to the mixing duct or chamber for causing portions of the heated moist air of the drying chamber to commingle with the cold air from the outside of the kiln before the

cold air reaches the drying chamber, whereby both heat and moisture are supplied to the cold air, and the latter raised to a higher temperature by the steam or heating pipes than is possible when cold air is conducted directly to the said pipes, as explained in the aforesaid application. The upper ends of the hot air ducts or passages communicate with the transversely disposed mixing duct or chamber at one end thereof.

The suction duct 8 is provided at a point intermediate of the top and bottom of the drying chamber with a horizontal partition 30, and it has an opening 31 located above the partition and communicating with the interior of the drying chamber. The upper portion of the suction duct passes through the mixing duct or chamber and is close to the same and is connected with a hooded chimney or stack 32, forming a continuation of the suction duct and adapted to create sufficient draft or suction to cause the circulation through the ducts or passages of the unit or section with which it is connected. Each chimney or stack is provided below its top or hood 32 with opposite outlets 33, and it is equipped with a suitable damper or valve 34, having exterior operating means 35 and adapted to be adjusted for controlling the draft or suction. While the exterior damper operating means is shown in the form of a rod, it may, of course, be of any other preferred construction. The cold air entering the kiln through the main inlet openings 25 passes into the cold air duct of each section or unit, and is drawn upward by the suction through the cold air duct into the mixing duct or compartment, where it thoroughly mixes with the heated moist air from the hot air ducts or passages. The mixture travels downwardly through the return ducts or passages to the transverse bottom ducts or passages and enters the drying chamber through the openings 21 and 22 in the floor thereof. In this manner the air, heat and moisture circulate around the drying chamber and through the alternate reversal of the sections or units the direction of circulation is reversed, which results in a thorough diffusion of heat, moisture and air, thereby securing the best conditions for the drying of lumber. Each set or series of ducts constituting a unit of the dry kiln performs the mixing suction and return functions independently of the other sets, and at the same time all of the sets operate in and around one drying chamber and in conjunction with a single heating means.

The kiln may be constructed of any desired capacity, and in the accompanying drawings it is shown with two tracks for the reception of kiln cars 36 upon which the lumber or other material to be dried may be loaded and arranged in any desired manner. The rails 37 of the tracks are sup-

ported upon standards or posts 38 in the usual manner. The standards or posts extend above the plane of the heating pipes, and the air passing upward through the 5 outlet openings of the lower transverse passages or ducts impinges against the heating pipes and is raised to a high temperature, and as it is moist by the mixture of a portion of the air of the drying chamber of the 10 kiln, it possesses greater advantages than highly heated dry air, it being a well known fact that a certain amount of moisture must remain in the kiln in order to keep the surface of the lumber soft and the pores open 15 to prevent warping, checking, hollow horning, case hardening and other injurious results. The moisture may be supplied to the kiln by any suitable means.

The vertical ducts or passages at opposite 20 sides of the units or sections may be arranged in various ways. In Fig. 10 of the drawings is illustrated one side of a unit comprising three ducts or passages and having a suction duct 39, arranged centrally 25 between combined cold air and hot air ducts or passages 40. The vertical ducts or passages 40 are provided at their lower ends with cold air inlet openings 41 and have openings 42 located at a point intermediate 30 of the upper and lower ends of the ducts or passages 40 and communicating with the drying chamber. By this construction, cold air from the outside of the kiln and heated moist air from the drying chamber are conducted through the same ducts or passages 35 to the mixing duct or chamber and the mixing action takes place before the cold air and the heated moist air enter the mixing duct or chamber.

40 In Figs. 11 and 12 is illustrated another arrangement of the vertical ducts or passages. In Fig. 11, which shows the vertical ducts or passages at one side of the unit, a centrally arranged cold air duct or passage 43 is located between hot air ducts or 45 passages 44, and the suction duct or passage 45 is located at the opposite side of the unit or section of the kiln between return ducts or passages 46, which conduct the mixture 50 from the mixing duct or chamber to the bottom of the drying chamber. The cold air duct 43 is provided at its lower end with an inlet opening 47, which communicates with the cold air space at the bottom of the 55 kiln, and the hot air ducts 44 are provided with openings 48, which communicate with the interior of the drying chamber. The return ducts 46 are provided at their lower 60 ends with openings 49, connected with the transverse bottom ducts or passages of the kiln.

The suction ducts 39 and 45 are provided with openings 50 and 51, which communicate with the drying chamber, and the upper 65 ends of the suction ducts 39 and 45 are con-

nected with hooded stacks or chimneys 52 and 53, constructed similar to those heretofore described. While the return ducts are located at the opposite side or end of the mixing chamber or duct from the cold air 70 duct, and the means for supplying the heated moist air, the suction ducts or passages may be located at either side of the drying chamber.

The dry kiln may be constructed in series, 75 as explained in the aforesaid application, or it may be provided with a single drying chamber, as shown in the accompanying drawings. The ends of the drying chamber are closed by suitable doors 54, which may 80 be of any preferred construction.

What is claimed is:—

1. A dry kiln including a drying chamber, heating means at the bottom thereof, a plurality of sets of ducts or passages each 85 comprising a mixing duct or chamber located at the top of the drying chamber, a cold air passage located at one end of the mixing duct or chamber and extending upward from the lower portion of the kiln to 90 the said mixing duct or chamber, a return duct extending from the other end of the mixing duct or chamber to the bottom of the drying chamber and communicating therewith, and means for conducting heated 95 air from the drying chamber to the mixing duct or chamber.

2. A dry kiln including a drying chamber, heating means at the bottom thereof, a plurality of sets of ducts or passages each 100 comprising a mixing duct or chamber located at the top of the drying chamber, a cold air passage located at one end of the mixing duct or chamber and extending upward from the lower portion of the kiln to 105 the said mixing duct or chamber, a return duct extending from the other end of the mixing duct or chamber to the bottom of the drying chamber and communicating therewith, and means for introducing the 110 heated moist air from the drying chamber into the mixing chamber at the same end as the cold air.

3. A dry kiln including a drying chamber, and a plurality of separate sets of ducts 115 or passages comprising separate mixing ducts or chambers located at the top of the drying chamber, ducts or passages connected with the mixing ducts or chambers at one end thereof for conducting cold air from the exterior of the kiln and heated moist air from the drying chamber to the said mixing ducts or chambers, return ducts extending downwardly from the other end of the mixing ducts or chambers to the bottom 120 of the kiln and communicating with the drying chamber, and a separate suction duct 125 for each of said sets of ducts or passages communicating with the drying chamber, and heating means located within the dry- 130

ing chamber and arranged in the path of the air entering the same.

4. A dry kiln including a drying chamber, and a plurality of sets of ducts or passages each comprising a mixing duct arranged across the top of the drying chamber from one side of the kiln to the other, a cold air duct extending upwardly from the lower portion of the kiln and connected with one end of the mixing duct, a return duct extending from the other end of the mixing duct, a hot air duct connected with the mixing duct at the same end as the cold air duct and extending downwardly from the mixing duct and communicating with the interior of the drying chamber for conducting heated moist air therefrom to the mixing chamber, a suction duct also communicating with the drying chamber, and a chimney or stack connected with the suction duct.

5. A dry kiln including a drying chamber, and a plurality of separate sets of ducts or passages comprising mixing ducts arranged at the top of the drying chamber, cold and hot air ducts connected with the mixing chamber at one end thereof for conducting cold air from the outside of the kiln and heated moist air from the drying chamber to the mixing chamber, return ducts connected with the mixing ducts at the other end thereof and extending therefrom to the lower portion of the kiln and communicating with the drying chamber at the bottom thereof, and suction ducts connected with the drying chamber, said sets of ducts or passages being reversed at intervals to arrange their corresponding ducts at opposite ends of the mixing ducts.

6. A dry kiln including a drying chamber, and separate sets of ducts or passages each comprising a transverse mixing duct extending across the top of the drying chamber, a vertical cold air duct extending from one end of the mixing duct to the lower portion of the kiln, a hot air duct located at the same end of the mixing duct as the cold air duct and communicating with the drying chamber for conducting heated moist air therefrom to the mixing duct, a plurality of return ducts extending from the other end of the mixing duct to the lower portion of the kiln and communicating with the drying chamber at the bottom thereof, a suction duct communicating with the drying chamber, and a chimney or stack connected with the suction duct.

7. A dry kiln including a drying chamber, and separate sets of ducts or passages each comprising a transverse mixing duct extending across the top of the drying chamber, a vertical cold air duct extending from one end of the mixing duct to the lower portion of the kiln, a hot air duct located at the same end of the mixing duct

as the cold air duct and communicating with the drying chamber for conducting heated moist air therefrom to the mixing duct, a plurality of return ducts extending from the other end of the mixing duct to the lower portion of the kiln and communicating with the drying chamber at the bottom thereof, a suction duct communicating with the drying chamber and closed to the same, and a chimney or stack connected with and forming a continuation of the suction duct.

8. A dry kiln including a drying chamber, a plurality of separate transverse mixing ducts extending across the top of the drying chamber and closed to the same at the top thereof, a plurality of ducts connected with each of the mixing ducts at one end thereof for conducting cold air from the outside of the kiln and heated moist air from the drying chamber to the mixing ducts, a plurality of return ducts connected with the other end of each of the mixing ducts and extending therefrom to the lower portion of the kiln and communicating with the drying chamber at the bottom thereof, and a plurality of chimneys or stacks connected with the drying chamber for creating a suction or draft through the said ducts.

9. A dry kiln including a drying chamber, a plurality of separate transverse mixing ducts extending across the top of the drying chamber, a cold air space or conduit located beneath the drying chamber, cold air ducts extending upward from the said cold air space or conduit and connected with one end of each of the mixing ducts, return ducts extending downward from the mixing ducts at the other end thereof to the lower portion of the kiln and communicating with the drying chamber at the bottom thereof, and hot air ducts connecting the mixing duct with the drying chamber.

10. A dry kiln including a drying chamber, a plurality of separate mixing ducts extending across the top of the drying chamber, a continuous cold air space or conduit arranged beneath the drying chamber, a plurality of lower transverse ducts located between the cold air space or conduit and the bottom of the drying chamber and communicating with the latter, cold air ducts extending upward from the cold air space or conduit to the mixing ducts at one end thereof, return ducts connected with the mixing ducts at the other end thereof and extending downward to and connected with the said lower transverse ducts, hot air ducts for conducting heated moist air from the drying chamber to the mixing duct, and chimneys or stacks connected with the drying chamber for causing a circulation through the said ducts.

11. A dry kiln including a drying chamber, separate transverse mixing ducts ex-

- tending across the top of the drying chamber, vertical ducts located at opposite sides of the kiln and connected with the mixing duct and having lower enlarged portions, 5 the ducts at one end of each mixing duct communicating with the outside air and with the drying chamber and the ducts at the other end of each mixing duct extending downward from the same to the lower portion 10 of the kiln and connected with the bottom of the drying chamber, separate suction ducts also communicating with the drying chamber, and chimneys or stacks connected with the suction ducts.
- 15 12. A dry kiln including a drying chamber, a plurality of separate transverse mixing ducts extending across the top of the drying chamber, a plurality of vertical cold and hot air ducts arranged in one end of 20 each of the mixing ducts and communicating with the outside atmosphere and with the drying chamber for conducting cold air and heated moist air to the mixing ducts, a plurality of vertical return ducts located 25 at the other end of each of the mixing ducts and extending downward therefrom to the lower portion of the drying chamber and communicating with the same, the said ducts at the ends of the mixing duct being alter- 30 nately reversed to arrange the cold and hot air ducts of the adjacent mixing ducts at opposite sides of the kiln for causing the air to circulate through the mixing ducts in opposite directions, and chimneys or stacks 35 connected with the drying chamber for producing a circulation through the said ducts.
13. A dry kiln including a drying chamber, heating means, a plurality of separate sets of ducts or passages, each set comprising a mixing duct or chamber located at the top of the drying chamber, a cold air passage located at one end of the mixing duct or chamber, a return duct extending from the other end of the mixing duct or chamber to the drying chamber and communicating therewith, and means for conducting heated moist air from the drying chamber to the mixing duct or chamber. 40
14. A dry kiln including a drying chamber, heating means, a plurality of separate sets of ducts or passages, each set comprising a mixing duct or chamber located at the top of the drying chamber and traversing the same from one of the walls of the kiln to the opposite wall thereof, a cold air passage located at one end of the mixing duct or chamber, a return duct extending from the other end of the mixing duct or chamber to the drying chamber and communicating therewith; and means for conducting heated moist air from the drying chamber to the mixing duct or chamber and for introducing it into the latter at the same end as the cold air. 45
- In testimony, that I claim the foregoing as my own, I have hereunto affixed my signature in the presence of two witnesses. 50
